DESIGN FOR A PASTE DISPENSER

James M. Nixon, Asheville, N. C.

Application April 3, 1939, Serial No. 83,999

Term of patent 3½ years

To all whom it may concern:

Be it known that I, James M. Nixon, a citizen of the United States and residing in the city of Asheville, county of Buncombe, and State of North Carolina, have invented a new, original, and ornamental Design for a Paste Dispenser, of which the following is a specification, reference being had to the accompanying drawing, forming a part thereof.

I claim:

The ornamental design for a paste dispenser, as shown.

JAMES M. NIXON.
